UNITED STATES PATENT OFFICE

FELIX MEYER, OF AACHEN, GERMANY

HYPODERMIC SYRINGE FOR INJECTING LIQUIDS INTO THE BODY OR FOR TAKING THEM THEREFROM

Original application filed November 7, 1924, Serial No. 748,390, and in Germany May 31, 1924. Divided and this application filed June 23, 1930. Serial No. 463,260.

This invention relates to hypodermic syringes for injecting liquids into the body or for taking them therefrom.

According to the present invention the 5 syringe is provided with an elastic stopper and a cannula carried by and passing through the said stopper and extending into the interior of the syringe, the part of the cannula projecting therein being opened or closed 10 with respect thereto by moving the stopper from the outside.

The substance with which the syringe is charged, is under pressure or the syringe contains a vacuum according as to whether the 15 fluid is to be injected into the body or substance to be drawn therefrom. The injecting into and the drawing from the body are effected with the aid of a cannula which is inserted into an existing aperture or into an 20 opening to be produced. In the latter case the cannula is fitted with a hollow metal needle preferably fused together therewith. The syringe is closed by a stopper consisting of rubber or of another suitable elastic mate- 25 rial which serves as a holder for the cannula. This cannula projects partly outside and partly inside the syringe. The part projecting into the syringe is separated from the interior of the syringe by a lid or casing which 30 is only opened when the syringe is to be applied. The opening is effected from the outside by moving the elastic stopper either directly, for instance by pressing, pulling or twisting the same, or by moving the cannula. 35 By opening the cannula a connection is established between the interior of the syringe and that of the cannula. In order to be able to interrupt the operation, the arrangement is such as to allow the said connection to open 40 and close at will by moving the stopper or the cannula. The part of the cannula projecting into the interior of the syringe may be shaped in such a manner that, when in a state of rest, it presses with its opening so 45 firmly against the elastic stopper, that the opening is thereby closed. By exerting a lateral pressure directly on to the part of the stopper projecting outside the syringe or on to the outer projecting part of the 50 cannula, the opening of its part projecting

into the syringe is forced away from the rubber stopper and is closed again when the pressure is released. The cannula is provided with a needle so that when the latter is driven into a blood vessel for instance 55 into a stopped vein, blood will enter into the cannula, the quantity and colour of the blood that has penetrated therein allowing an opinion to be formed as to whether a certain kind of blood vessel has been struck or not. The 60 inner part of the cannula may be so constructed that it is normally completely closed, an opening being produced therein by a portion of the said inner part of the cannula being broken off, such breaking being 65 caused also by moving the stopper or the outer part of the cannula. Also in this case the part of the cannula projecting into the 70 syringe may be so constructed that the opening of the remaining part of the cannula 75 bears against an elastic cover which closes the opening when the stopper is in a certain position.

Referring to the accompanying drawings Figure 1 shows a syringe for injecting fluids 75 into an existing or natural opening of the body. The inner end of the cannula K_1 carried by the rubber stopper P_1 and projecting into the syringe is bent at a right angle, and the opening of this bent portion bears firmly 80 against the inner wall of the rubber stopper P_1 . By bending the stopper, the latter and the cannula assume the position indicated in dotted lines and the cannula K_1 is opened 85 to the interior of the syringe.

Figure 2 shows a similar construction which is however fitted with a hollow metal needle N_2 for injecting liquids into the tissue of the body. S_2 is a sheath enclosing the needle, which sheath is removed when the 90 syringe is to be used.

Figure 3 shows the same arrangement as Figure 2. The end of the cannula K_2 in this construction is provided with a hollow chamber H_3 into which the blood can enter and which forms the indicating device hereinbefore described. The cannula also has a lateral open extension which can be closed and opened with respect to the interior of the 95 syringe as hereinbefore described.

The hollow chamber H_3 forming the indicating device may however be so arranged as to follow directly the hollow needle and to extend partly outside the syringe for instance between the outer end of the stopper and the hollow needle. This modification which is illustrated in Figure 4 and in which K_4 is the cannula, H_4 the hollow chamber, P_4 the stopper and N_4 the hollow needle, is of special advantage, when an opaque injecting liquid is used through which the blood cannot be seen.

In Figure 5 the cannula K_5 within the syringe is completely closed and is broken at a certain weak point by moving the stopper P_5 so that the end of the cannula K_5 is pressed against the inner wall of the syringe.

In Figure 6 the cannula K_6 is so shaped that after it has been broken at a weak point in the manner described with reference to Figure 5, the opening that is thereby left in the cannula may be closed from the outside by pressing the cannula against the inner wall of the stopper P_6 .

The invention also relates to a simple process for evacuating syringes of the kind above described or for filling them with liquids or gases under pressure. For this purpose a hollow needle F as shown in Figures 4 and 7 is passed through the stopper P_7 until its end projects into the interior of the syringe. This hollow needle F is connected at its other end to a gas- or liquid supply. The gas contained in the closed syringe is either drawn off through the hollow needle F so that a vacuum is produced therein, or the gas is driven into the syringe by pressure so that the latter contains compressed gas, or a liquid is forced into the syringe through the needle F , whereby the gas in the syringe is compressed, so that when the cannula K_7 is subsequently opened to the interior of the syringe the gas, in consequence of its expansion, forces the liquid out of the syringe again. After the syringe has been evacuated or filled, the hollow needle F is pulled out whereupon the rubber stopper P_7 automatically closes at the point where it has been pierced.

What I claim is:—

In a device of the character described including a needle, a mounting and a transparent container having an internal pressure different to that of the atmosphere, and adapted for communication with the needle, a frangible capillary tube seal of transparent material forming initially a continuation of the passage through the needle from the inner end of the needle within said container.

In testimony whereof I have signed my name to this specification.

FELIX MEYER.
